(57) **CLAIM**

The ornamental design for a siding hanging gauge, as shown and described.

DESCRIPTION

FIG. 1 is an upper front left perspective view of the siding installation gauge.

FIG. 2 is a lower front perspective view thereof.

FIG. 3 is an upper rear left perspective view thereof.

FIG. 4 is a lower rear left perspective view thereof.

FIG. 5 is an upper front right perspective view thereof.

FIG. 6 is a lower front right perspective view thereof.

FIG. 7 is an upper rear right perspective view thereof.

FIG. 8 is a lower rear right perspective view thereof.

FIG. 9 is a front view thereof.

FIG. 10 is a left side view thereof.

FIG. 11 is a right side view thereof.

FIG. 12 is a rear side view thereof.

FIG. 13 is a top view thereof.

FIG. 14 is a bottom view thereof; and,

FIG. 15 is a flat view of the article in a flattened alternative configuration.

1 Claim, 8 Drawing Sheets
